Attorney

UNITED STATES PATENT OFFICE.

JOAQUIN SAYROLIS VALERO, OF BARCELONA, SPAIN.

SAFETY DEVICE FOR SMOKERS.

Application filed March 6, 1926, Serial No. 92,834, and in Spain March 24, 1925.

This invention relates to a safety device which prevents sparks or ashes from falling from the cigarette or cigar which is being smoked, thus avoiding the burning of objects by the sparks falling from the cigarette or cigar, and also preventing the ash from soiling the clothes, furniture, carpets, etc.

This safety device is therefore not only a great protector, preventing the destruction or spoiling of many objects, but it is also a means of avoiding the soiling of the contents of a house.

It is well known how much annoyance is caused by the dropping of ash and particles of burning tobacco, whether it be when lying in bed, during the taking of meals, in the office, or even when walking. It is unnecessary to enumerate the number of articles of clothing, and the number of pieces of furniture, carpets, sheets, counterpanes, etc., which have been soiled or burnt by the said particles.

The safety device which is the object of this invention tends to avoid these inconveniences.

This safety device is essentially composed of a case, manufactured of a noninflammable material, the form of which adapts itself to that of a cigar or cigarette. One of its ends is open so that the lower end of the cigarette, or cigar, that is to say the end which is put into the mouth for smoking, may project. Further, the case is manufactured of perforated sheet metal or metallic network, and the apertures let the air pass through without allowing any ash or particles of tobacco to escape.

Preferably it will be manufactured in such a manner that its main body be formed of a metallic cloth mounted on a frame composed of very fine metal rods. Its upper part is rounded to adapt itself to the form of the cigarette or cigar. The cigarette or cigar which is smoked inside this case cannot do any damage, nor can it become dangerous in the slightest degree, for it is simply impossible for burning particles or ash to pass through the openings. When provided with this case it will be possible to smoke with ease on ships, aeroplanes, and even in mines, for not even an ignition of gases can take

place through the cigar or cigarette when it is smoked inside the said case.

In the attached drawings, which form an essential part of this invention a form of execution is shown as follows:

Fig. 1 is a side view of the device when closed.

Fig. 2 is the same device seen from the mouthpiece.

Fig. 3 is a side view of the device when open.

Fig. 4 is an end view of Fig. 3.

The drawings show in detail the following: —1— a rigid frame on which are mounted the two parts formed of metallic cloth or perforated sheet metal —2—. The two parts are united in such a manner that they can be opened or closed. In the drawings can be seen a ring —4—, the two halves of which can be united by means of the hinge —3—. One of the said halves of the ring carries an extension —5—. The said extension is imprisoned below the sliding piece —6— fixed on the stud —8— for the handle or support of the case —7—.

It is understood that the closing and retaining device of the apparatus can be freely modified, without departing from the idea of the invention.

The lighted cigarette or cigar is placed in the case in such a way that the end projects through the aperture —9— of the same, and when it is being smoked the air will be introduced through the holes or perforations in the metallic walls —2—. In this manner it will be possible to smoke without any danger whatever of burning or setting light to anything, or of spoiling or soiling anything in automobiles, steamers, tramways, rooms, in bed, or even in places where explosive gases or easily inflammable materials are present, such as petroleum, gasoline, benzine, powder, etc.

The advantages of this apparatus are so evident that it will not be necessary to insist on them.

I claim:

A cigar or cigarette ash protector, comprising in combination two parts of a perforated cover designed to cover the cigar or cigarette, one half of a flat ring fixed at

the middle of each cover part, a hinge for hingedly connecting the inner ends of said two ring parts, an extension on the outer end of one of the said ring parts, a stud on the outer end of the other ring part and arranged for receiving said extension, a sleeve slidably mounted on said stud so that

it can be pushed over said extension when the protector is closed, and a ring-shaped handle on said stud serving as holder for the protector.

In testimony whereof I have affixed my signature.

JOAQUIN SAYROLS VALERO.
